Attorneys

UNITED STATES PATENT OFFICE

EARL E. EICKMEYER, OF DAYTON, OHIO, ASSIGNOR TO THE DAYTON PUMP AND MFG. CO., OF DAYTON, OHIO, A CORPORATION OF OHIO

SETTING MECHANISM FOR PUMPS

Original application filed October 31, 1928, Serial No. 316,246. Divided and this application filed February 8, 1929. Serial No. 338,364.

This invention relates to improvements in gasoline filling pumps.

It particularly relates to accurate means for determining the quantity of gasoline to be delivered to the customer, and after the quantity has been accurately determined the apparatus can not be disturbed so as to vary the amount of gas to be delivered.

It is a further object of this invention to provide a pump in which the valve controlling the delivery of gasoline from a visible container to the automobile is locked against being opened until the handle of the setting mechanism is in operative setting position.

It is a still further object of this invention to provide adjustable means for the positioning of the operating handle for the purpose of determining accurately the amount of gasoline to be delivered to an automobile, or any other container for receiving the delivered gasoline.

It is particularly an object of this invention to provide means for adjustably positioning the handle that controls the delivery of gasoline in such a way as to accommodate the position of the handle to the particular varying features of the bowl from which the gasoline is delivered to the purchaser.

It frequently happens that bowls vary in diameter in different parts of the length of the bowl, and the adjustable features of the handle and means for positioning the handle are for the purpose of so positioning the handle that an accurate amount of gasoline will be delivered regardless of these slight variations in the size of the bowl in different parts of the bowl.

These and other advantages will appear from the following description, taken in connection with the drawings.

Referring to the drawings:

Figure 1 is a vertical section through a part of the bowl and the lever mechanism for determining the amount of gasoline to be delivered.

Figure 2 is a face view of the drum, and shows the adjustable means for determining the position of the handle.

Figure 3 is a similar view with the annular plate removed.

This application is a division of application, Ser. No. 316,246, for gasoline pumps, filed October 31, 1928, and relates particularly to the features for adjusting the measuring tube.

The numeral 1 indicates the casing composed of a mesh of heavy wire surrounding the bowl 2, for the purpose of protecting the bowl. The bowl is of the usual type found in apparatus of this type, and is supported by the usual frame. The numeral 3 is used to indicate the measuring tube, which determines the quantity of gasoline to be delivered to the purchaser. The measuring tube is supported by a measuring rod 4, attached at its lower end to a bracket 5. The bracket 5 is supported by a spring-supported rod 6, and is adapted to move up and down thereon through the action of the rack bar 7, which is actuated by a gear 8.

The spring and rod 6 are supported by a fixed bracket 6', attached to some part of the frame that supports the bowl and the other part of the apparatus. The gear 8 that operates the rack bar is suitably mounted on the inner end of a tube member 9. The tube member 9 is rotatably supported by a tubular casing 9', and has on the outer end thereof a plate 10. This plate 10 and the gear 8 hold the tube 9 against longitudinal motion but permit the free rotation thereof.

Extending from the central part of the plate 10 are two ear members 11, to which is pivotally attached a setting handle 12. On the setting handle 12 at opposite sides of the pivot formed by the ears 11, there are pins, one a locking pin 13 extending from the outer end of the handle through the tube member, and adapted to extend beyond the tube member into the inside of the casing that surrounds the operating features here described and shown. The other pin is indicated by the numeral 14 and is called a setting pin, and will be more specifically described later.

The tubular casing is supported by and extends rearwardly from the central part of a setting drum 15. In the central part of

this drum is a hub member 16, through which the locking pin passes as it passes through the tubular casing. The setting drum is circular in shape and has located in the 5 annular space between the hub and the outer periphery thereof, a plurality of jaws 17. These jaws are each composed of parallel spaced members, one of which has a beveled surface 18, and provide space for the reception 10 of the setting pin 14. Each jaw is pivotally mounted to the floor of the drum by means of pivot members 19, so that a certain amount of adjustment is permitted to the jaws.

15 Extending from each pair of jaws is an arm 20, which has a screw threaded hole therein for the reception of a screw 21, which has on its inner end a head 22. For each screw 21 there is a corresponding screw 23 20 in the hub. These screws have heads 24. The purpose of the screws 21 is to adjust the jaws to accurately determine the position of the setting handle to deliver the correct amount of gasoline. The adjustment of these 25 jaws is effected by rotating the screw 21 by means of the head 22, and after the jaws have been properly adjusted the screws 21 may be locked by means of the screws 23 so that they will not further rotate until the screws 30 23 are released.

Pivotaly supported on the pivot of each pair of jaws is a centering plate 25. This plate is clearly shown in Figure 2, and is pivotally supported at the points 19. Each of 35 these plates has a slot 26 through which the setting pin passes as it enters in the space between the jaws. Each of these plates is held in place by means of a spring 27, which is attached to the plate at one end and to the 40 screws 21 at the other. Should the slot 26 of any centering plate 25 not register with the opening between the pawls 17 the plate may be rotated on its pivot against the action of spring 27 until they do register. This alignment is usually effected by the setting pin 14, but other means may be used for this purpose.

45 There is placed over the centering plates an annular plate 28, which is held in place by the same pivot member 19, which are screws that serve as the pivot for the jaws and the centering plates. The annular plate has adjacent the setting plate a notch therein 29 so that access may be had to the centering plate and the jaws by the setting pin 14.

50 Slidably supported on the upper end of the stationary rod 6 is a stop member 30, which has a rod 31 extending upwardly therefrom and connects the stop member with the handle that operates the valve to control the delivery 55 of gasoline from the bowl. In the operation of the handle to deliver gasoline from the bowl the stop member 30 is pressed down against the action of a spring 32, supported at its lower end on the bracket 6'. If the stop member 30 should be held against movement

60 by means of the lock pin 13 it would be impossible to open the valve for the delivery of gasoline. The position of the lock pin, as shown in Figure 1, is removed from engagement with the stop 30 because in this position the setting pin is in engagement with the jaws 65 in the drum for the purpose of determining the amount of gasoline to be delivered.

65 For the purpose of determining the amount of gasoline to be delivered, the handle with the lock pin 13 inserted so as to engage under the stop 30 with the setting pin withdrawn from engagement with the jaws, is rotated until the setting pin comes in position to be inserted in the pair of jaws opposite the member indicating the quantity of gasoline to be delivered. With the handle in this position 70 the lock pin 13 is withdrawn and the setting pin inserted between the jaws for the purpose of determining the amount of gasoline to be delivered.

75 When the handle has been thus adjusted and the pin inserted into the space between the jaws 17, the lock pin 13 is withdrawn from the stop 30 and the handle for the purpose of opening the delivery valve from the bowl can be operated to deliver the amount of gasoline required. Of course, it is to be understood that the bowl has been previously filled, or will be filled, and the amount of gasoline 80 delivered is the difference between the full capacity of the bowl and that down to the upper surface of the measuring tube, and the position of the measuring tube is determined by the positioning of the handle in the proper jaw, and this jaw has been set or adjusted so as to assure the delivery of the correct amount of gasoline.

85 For the purpose of holding the lock pin 13 in its two positions, there is provided a 85 plunger 33, which is adapted to engage in either one of two notches 34 in the upper surface of the pin 13. In one position the lock pin is held in the position shown in Figure 1; in the other position the pin is inserted or pushed into the casing so that the inner end of the pin engages beneath the stop member 30 so as to prevent the operation of the lever that opens the valve to deliver gasoline to the purchaser and from the bowl 2.

90 The whole structure shown here is supported by the usual rods 35, that are properly inclosed in a casing usually found in apparatus of this kind.

95 I desire to comprehend within my invention such modifications as may be clearly embraced within my claims and the scope of my invention.

Having thus fully described my invention, what I claim is new and desire to secure by Letters Patent, is:

100 1. In a gasoline dispensing pump in combination with a bowl and a measuring tube, an operating handle pivotally supported for adjusting said tube, means for positioning said

handle in its adjustment of said tube, said means including a plurality of adjustable jaws, and a plurality of centering plates.

2. In a gasoline dispensing pump in combination with a bowl and a measuring tube, an operating handle pivotally supported for adjusting said tube, means for positioning said handle in its adjustment of said tube, said means including a plurality of adjustable jaws, and a plurality of centering plates pivotally mounted on said jaws.

3. In a gasoline dispensing pump in combination with a bowl and a measuring tube, an operating handle pivotally supported for adjusting said tube, and means for positioning said handle in its adjustment of said tube, said means including a pin on said handle and a plurality of adjustable jaws for receiving said pin, and a plurality of guide plates for said pin mounted on said jaws.

4. In a gasoline dispensing pump in combination with a bowl and a measuring tube, an operating handle pivotally supported for adjusting said tube, and means for positioning said handle in its adjustment of said tube, said means including a pin on said handle and a plurality of adjustable jaws for receiving said pin, and a plurality of guide plates for said pin pivotally mounted on said jaws.

5. In a gasoline dispensing pump in combination with a bowl and a measuring tube, a drum, a handle supported in relation to said drum for adjusting said tube and having an adjusting pin thereon, and means in said drum to receive said pin for positioning said handle in the adjustment of said tube, said means including a plurality of jaws and guide plates.

6. In a gasoline dispensing pump in combination with a bowl and a measuring tube, a drum, a handle supported in relation to said drum for adjusting said tube and having an adjusting pin thereon, and means in said drum to receive said pin for positioning said handle in the adjustment of said tube, said means including a plurality of adjustable jaws and guide plates.

7. In a gasoline dispensing pump in combination with a bowl and a measuring tube, a drum, a handle supported in relation to said drum for adjusting said tube and having an adjusting pin thereon, and means in said drum to receive said pin for positioning said handle in the adjustment of said tube, said means including a plurality of adjustable jaws and a plurality of pivotally mounted guide plates.

8. In a gasoline dispensing pump in combination with a bowl and a measuring tube, a drum, a handle supported in relation to said drum for adjusting said tube and having an adjusting pin thereon, and means in said drum to receive said pin for positioning said handle in the adjustment of said tube, said means including a plurality of adjustable

jaws and a plurality of pivotally mounted spring operated guide plates.

9. In a gasoline dispensing pump in combination with a bowl and a measuring tube, a handle for adjusting said measuring tube, a pin on said handle to prevent the delivery of gasoline from said bowl while the handle is being operated, a second pin on said handle, and adjustable means to receive said second pin to determine accurately the amount of gasoline to be delivered.

10. In a gasoline dispensing pump in combination with a bowl and a measuring tube, a swinging handle for adjusting said measuring tube, a pin on said handle adapted to prevent the delivery of gasoline from said bowl while the handle is being operated, a second pin on said handle, and adjustable jaw means to receive said second pin to determine the amount of gasoline to be delivered, said pins being operated by the swing of the handle.

11. In a gasoline dispensing apparatus in combination with a bowl and a measuring tube, a rotating and swinging handle for adjusting said tube, means operated by swinging the handle into one position for preventing the delivery of gasoline, and means operated by swinging the handle to another position to lock the tube in adjusted position.

12. In a gasoline dispensing apparatus in combination with a bowl and a measuring tube, a plate for adjusting said tube, a handle pivoted to said plate, a pin on said handle adapted to prevent the delivery of gasoline from said bowl while the tube is being adjusted, and a second pin on said handle to lock the tube in adjusted position, said pins being operated by swinging the handle on said plate.

13. In a gasoline dispensing apparatus in combination with a bowl and a measuring tube, a plate pivotally supported at one end and operable to adjust said tube, said plate having a hole in each end, a handle pivotally supported on said plate to operate said plate, a pin extending from said handle through the hole in the pivot end of said plate and adapted when in one position to prevent the delivery of gasoline, a second pin on said handle extending through the hole in the other end of said plate, and means adapted to be engaged by said second pin to lock the tube in adjusted position when said first pin is in another position to permit the delivery of gasoline.

14. In a liquid dispensing apparatus, a bowl, a measuring tube extending into said bowl, a drum, a hub in said drum having a hole therein, a plate pivotally mounted at one end on said hub to adjust said tube and having a hole in the other end, a handle pivoted on said plate to operate said plate, a pin attached to said handle and extending

through said hub and adapted when in one position to prevent the delivery of liquid while the tube is being adjusted, a second pin extending from said handle and through the hole in the other end of said plate, and adjustable means in said drum to be engaged by the second pin to lock the tube in adjusted position, said pins being so operated by the handle that when the first pin is in a position to permit delivery of liquid the second pin is idle and when the second pin engages said drum the first pin is idle.

In testimony whereof, I affix my signature.
EARL E. EICKMEYER.
